UNITED STATES PATENT OFFICE.

BENJAMIN MARKOWITZ, OF NEW YORK, N. Y., ASSIGNOR TO AMERICAN STEEL FRAME & BAND IRON COMPANY, OF NEW YORK, N. Y., A CORPORATION OF NEW YORK.

HANDLE.

1,000,739.

Specification of Letters Patent. Patented Aug. 15, 1911.

Application filed March 16, 1911. Serial No. 614,829.

To all whom it may concern:

Be it known that I, BENJAMIN MARKOWITZ, a citizen of the United States, residing in the borough of the Bronx, in the city, 5 county, and State of New York, have invented certain new and useful Improvements in Handles, of which the following is a full, clear, and complete disclosure.

My invention relates to handles which are 10 usually composed of a metallic core or frame covered with leather or other similar elastic material and adapted to be attached to a bag or suitcase by means of suitable rings riveted to the frame of the bag or suitcase. 15 Heretofore in the manufacture of cores or frames for handles, it has been customary to use a piece of wire, the ends of which have been enlarged by casting or molding on the ends thereof knobs of metal, such as lead, 20 and which have holes passing therethrough to receive the rings on the frame of the bag.

The object of my invention is to substitute for this construction, a more simple and stronger arrangement of the wire, which 25 will not only cheapen the cost of manufacture, but provide a more durable and effective article.

For a detailed description of several forms 30 of my invention, which I at present deem preferable, reference may be had to the following specification and to the accompanying drawing, in which;

Figure 1 is a side elevation of a handle 35 showing in dotted lines my improved core or frame therein. Fig. 2 is an end view of the wire illustrated in Fig. 1, separated from the covering of the handle. Fig. 3 is a view taken at right angles to that of Fig. 2. Figs. 4 and 5 are plan views of modified 40 forms.

Referring to the drawing, the numeral 1 indicates the frame or wire base of the handle which terminates at each end in helical coils 2 which are formed on said wire during the process of manufacture. Said coils 45 2 are preferably connected with the straight portion 1 of the wire by means of an angular bend 3, so that the axial line of the main portion of the wire will pass through 50 the center portion of the coil at substantially right angles to the axis thereof.

In the modification shown in Fig. 4, the end of the coil instead of terminating with the last convolution, is continued and bent back at an angle, as indicated at 4, its end 55 being provided with a hook 5 which is bent about the end or shank of the handle where the angular portion 3 extends laterally. This construction makes a coil somewhat more rigid, and prevents the same from 60 twisting.

In Fig. 5 the modification is similar to that of Figs. 1, 2 and 3, with the exception that the helix formed on the end of the wire is enlarged at its outer ends, as indicated at 6, so as to conform more closely 65 with the shape of the rings 7 by which the handle is attached to the bag or suitcase.

Having described these forms of my invention, what I claim and desire to protect 70 by Letters Patent is:

1. In a handle, a core composed of a single wire and having transverse helices formed on the ends thereof, the lateral ends of said helices being situated symmetrically 75 on each side of the axis of said core.

2. In a handle, a core composed of a single wire having transverse helices formed integrally on the ends thereof, said wire being bent laterally and connected with one 80 end of each of said coils, so that the axis of the core passes transversely through the helices midway their ends.

3. In a handle, a core composed of a single wire having transverse helices formed 85 on the ends thereof and situated symmetrically on each side of the axis of said core, the ends of said helices being bent laterally thereof and fixed to the main shank of said core. 90

4. In a handle, a metallic core, a fibrous covering completely inclosing the same, said core comprising transverse wire helices located within said covering at its ends, and a central wire rigidly connecting said helices 95 at points intermediate their ends.

Signed at the city, county and State of New York, this 14th day of March, 1911.

BENJAMIN MARKOWITZ.
